UNITED STATES PATENT OFFICE.

JOHN F. KIRGAN, OF PHILLIPSBURG, NEW JERSEY, ASSIGNOR TO INGERSOLL-BAND COMPANY, OF JERSEY CITY, NEW JERSEY, A CORPORATION OF NEW JERSEY.

JET AUGMENTER OR EJECTOR.

Application filed August 18, 1922. Serial No. 582,740.

To all whom it may concern:

Be it known that I, JOHN F. KIRGAN, a citizen of the United States, and a resident of Phillipsburg, county of Warren, State of New Jersey, have invented a certain Jet Augmenter or Ejector, of which the following is a specification, accompanied by drawings.

This invention relates to jet augmenters or 10 ejectors, more particularly for augmenting fluid pressure in any desired apparatus, such as a condenser, cooler or similar vessel, by means of fluid jets, in which the fluids are separated into a plurality of separate enveloping layers or strata, which later commingle.

The primary object of the invention is to simplify and improve the construction of the 20 augmenter or ejector and to cause the steam to be emitted from the nozzle in the form of a hollow cylindrical jet or envelope, so that a large area is provided inside and outside of the jet or envelope of steam for the entrainment of the air and other vapors from 25 the condenser.

A further object is to construct a ring nozzle and diffuser of few parts and of such shape that they effectively cooperate with each other to cause the steam to be emitted 30 from the nozzle in the form of a ring jet or envelope surrounding an inner jet of air and vapor, the steam jet being itself surrounded by an outer envelope of air or vapor, the outer envelope of air being surrounded by an envelope of cooling water.

Another object is to introduce the cooling 40 water at a point in the diffuser body, and in a manner, which is most effective for cooling purposes and to obtain a certain condensing effect.

Further objects will later appear and to the ends set forth my invention consists in the features of construction and operation described in the following specification and 45 illustrated in one of its preferred forms in the accompanying drawings, in which—

Figure 1 is a longitudinal sectional elevation of an ejector, and

Figure 2 is a plan view of the nozzle end 50 of the ejector body.

Referring to the drawings, the body portion or diffuser A of the ejector is cast or otherwise constructed in one piece, and as shown is formed with the contracted throat B having the enlarged outlet C at one end

of the body, preferably surrounded by the securing flange D which may be provided with securing apertures and fastening means (not shown), by means of which the ejector is secured in position on the desired apparatus with which it is to be used. The inlet E of the ejector, for air or other vapor, or both, is preferably formed separately from the body and extends at an angle to the longitudinal axis of the ejector. In this instance the inlet E is shown at right angles to said axis and is provided with the securing flange H. The inlet head G is threaded to the enlarged diameter portion J of the body A as shown at K.

A nozzle aperture L is provided at the top of the inlet head G for the insertion of a nozzle body O in axial alignment with the throat B. It is important that the nozzle aperture L shall be concentric with the throat of the diffuser for good operation. The nozzle body O is provided with an externally screw threaded portion P which is adapted to cooperate with a screw threaded portion Q of the nozzle aperture L for removably connecting the nozzle body O to the head G.

A nut R is preferably formed on the outer end of the nozzle body O to facilitate adjustment, and also to provide a connection 55 between an inlet aperture S in the nozzle body O and an exterior source of fluid supply (not shown) but which may be steam, by means of a pipe T. The nozzle flange U is adapted to bear against the head G and form a tight joint and the meeting surfaces of the flange U and head G are preferably machined so as to be true with each other, and the parts are preferably constructed and adjusted with the outlet of the nozzle in proper 60 position relative to the throat B, although the nozzle body O may be adjusted longitudinally in different positions if required by inserting a spacer in the form of a washer or packing material between the meeting 65 surfaces of the flange U and the head G.

The nozzle body O is formed with an inner tubular extension V, an outer annular flange W, and an annular chamber X between the tubular extension V and flange W. 70 The tubular extension V projects slightly beyond the end of the flange W and the outer cylindrical wall of the extension V gradually decreases in diameter toward the outer end beginning at a point Y just above 75

the end of the flange W. An annular ring or cap Z having a reduced diameter screw threaded portion a is adapted to be threaded into the flange W which is provided with 5 internal screw threads b for this purpose.

The ring Z surrounds the end of the tubular extension V and the opening in the ring Z is of slightly greater diameter than the widest portion Y of the tubular extension 10 V, so that an annular passage or ring c is formed between the ring Z and tubular extension V, this ring c gradually increasing in volume beginning at the point Y. A longitudinal passage d located in one side 15 of the nozzle body O maintains communication between the chamber X and the steam inlet T. The longitudinal cylindrical chamber e formed in the tubular extension V concentrically with the ring passage c communicates with a transverse passage f in the 20 nozzle body leading from the inner end L of the head G, and the passage f is open to communication with the inlet E.

A tubular nozzle g is formed integrally 25 with the head G and this nozzle g is provided with an interior convergent-divergent passage h and extends into the throat B of the body A, terminating at a point approximately in alignment with the narrowest portion 30 of the contracted throat B. An annular chamber j is formed within the enlarged portion J of the body A, this chamber surrounding the nozzle g and being adapted to convey water or other liquid from an inlet pipe connection k and past the end of 35 the nozzle g as shown at p to the interior of the diffuser body A. The nozzle g is located at a point remote from the nozzle body O and the position of the nozzle g 40 may be adjusted longitudinally and the volume of the annular passage j may be increased by interposing a spacer between the head G and the portion J of the body A.

Live steam entering the nozzle through 45 the steam connection T, passing through the communicating passage d into the annular chamber X and from thence to the ring passage c in the end of the nozzle, is adapted to flow into the throat h and through the 50 diffuser A in the form of an envelope or ring as shown at q surrounding the air or vapor, or both, passing from the inlet E to the end of the chamber within the head G and into and through the communicating 55 passages f and e, and out of the passage e as shown at r. The envelope of steam is itself surrounded by an outer envelope of 60 the same medium which flows through the passages f and e, this outer envelope being composed of fluid from the inlet E flowing around the sides of the nozzle within the 65 inlet head G and downwardly past the end of the nozzle between the interior wall of the head G and nozzle g, and the envelope 70 of steam as seen at s. The mixture flowing

into the throat h thus consists of an outer envelope of air or vapor, surrounding an envelope of steam and a core of vapor or air from the same source as the vapor or air of the outer ring. The several enveloping strata q, r, s decrease in volume upon entering the convergent-divergent passage h of the nozzle g, and upon entering the throat portion B of the diffuser an envelope of cooling water or other liquid is projected past the end of nozzle g around the outside of the vaporous mass. The mixture flowing through the diffuser thus consists of an inner core of vapor or air, an envelope of steam, an envelope of vapor or air, 80 and an outer envelope of cooling liquid, the mixture being emitted from the enlarged outlet C with all its elements effectively commingled.

The construction of the ring nozzle permits the envelope of steam to present a large area for the entrainment of the air or other vapor, both inside and outside of the steam envelope and the provision of the cooling chamber j around the nozzle g serves to present a cooled impinging surface for the steam and other constituents, resulting in the production of an appreciable condensing effect which is further augmented by the introduction of the cooling liquid around the 95 outside of the mixture at the throat B. This tends to higher efficiency of the apparatus through the most effective utilization of the principles of pressure augmentation and condensation which are desirable and necessary to obtain the best results with ejectors of the type for which the present invention is adapted.

What I claim is:

1. A jet augmenter or ejector comprising 100 a body portion having a fluid inlet, throat and outlet, a nozzle connected to said body portion and extending into said inlet, a passage in said nozzle communicating with said inlet through which fluid from said inlet is 105 adapted to be drawn, an annular passage in said nozzle surrounding said first mentioned passage adapted to project into said throat an envelope of fluid different from the inlet fluid, said envelope of fluid being adapted 110 to be surrounded by an envelope of inlet fluid and a second nozzle on said body portion adjacent said throat for supplying to the mixture of previously mentioned fluids a fluid different from either of the other 115 fluids.

2. A jet augmenter or ejector comprising 120 a body portion having a fluid inlet, throat and outlet, a nozzle connected to said body portion and extending into said inlet, a passage in said nozzle communicating with said inlet through which air is adapted to be 125 drawn from said inlet, an annular passage in said nozzle surrounding said air passage adapted to project into said throat an en- 130

velope of steam, said steam envelope being adapted to be surrounded by an envelope of air from said inlet and a second nozzle on said body portion adjacent said throat for supplying to the mixture of air and steam an envelope of liquid.

3. A jet augmenter or ejector comprising a body portion having a fluid inlet, throat and outlet, a nozzle removably connected to said body portion and extending into said inlet, a passage in said nozzle communicating with said inlet through which air from said inlet is adapted to be drawn, an annular passage in said nozzle surrounding

said air passage adapted to project into said throat an envelope of steam, said steam envelope being adapted to be surrounded by an envelope of air from said inlet, a second nozzle formed on said body portion and extending into said throat and an annular chamber surrounding said last mentioned nozzle adapted to be supplied with liquid for projecting an envelope of liquid to the mixture of steam and air.

In testimony whereof I have signed this specification.

JOHN F. KIRGAN.
